UNITED STATES PATENT OFFICE.

WILHELM GEDOR ALDEEN, OF ROCKFORD, ILLINOIS.

PHONOGRAPH OR LIKE CABINET.

Application filed July 3, 1920. Serial No. 393,924.

To all whom it may concern:

Be it known that I, WILHELM G. ALDEEN, a citizen of the United States, residing at Rockford, in the county of Winnebago and 5 State of Illinois, have invented certain new and useful Improvements in Phonograph or like Cabinets.

The invention relates to cabinets for phonographs and the like, and has for its 10 general object the provision of an improved counterbalancing device for the cover or hood of the cabinet.

A more specific object of the invention is to provide a counterbalancing device where- 15 in a torsion spring is advantageously em- ployed to resist the action of gravity in the varying degree required to balance the cover in any open position, and to be automatically held out of actuating engagement 20 when the cover is closed, the device being substantially noiseless in operation, durable and otherwise of an efficient and practical character.

Counterbalancing devices in common use 25 in phonograph or like cabinets are of such character that as the hood or cover ap- proaches its lowermost position, the springs employed are so tensioned that in spite of the increased pressure exerted thereon by 30 the hood as it approaches the horizontal, the lifting effect of the springs is so in- creased that it becomes necessary for the operator or user to take particular pains to see that the hood is in fact closed.

35 A further objection to the commonly used devices is that when the hood is closed the cabinet and hood must sustain a constant strain on account of the increased spring tension in that position, resulting eventually 40 in warping the walls of the cabinet.

The present invention aims to overcome these objections by providing a counter- 45 balancing device which while capable of maintaining the hood or cover in its raised position will permit it to descend by gravity into closed position after having been moved substantially into such position, and when closed will relieve the hood and cabinet of the otherwise constant strain resulting from the spring tension which tends to warp 50 the parts to which the device is attached.

Another object of the invention is to pro- 55 vide a counterbalancing device which is capable of easy adjustment to vary the lift- ing or counterbalancing effect thereof.

A further object of the invention is to

provide a counterbalancing device of a practical character in that it is of comparatively simple construction and may be readily assembled.

The objects of the invention thus generally stated, together with other and ancillary advantages, may be obtained by the construction and arrangement illustrated in the accompanying drawings forming 65 part hereof in which Figure 1 is a fragmentary sectional view through the upper portion of a phonograph cabinet, having my improved counterbalancing device applied thereto, and showing the position of the 70 parts when the hood is closed, with that portion of the spring supporting member indicated below the line 3-3 in Fig. 2 re- moved. Fig. 2 is a horizontal sectional view on a reduced scale, taken on line 2-2 of 75 Fig. 1. Fig. 3 is a sectional view taken on the line 3-3 of Fig. 2 and showing the construction permitting the adjustment of the counterbalancing spring. Fig. 4 is a fragmentary elevation showing a detail of 80 construction which facilitates assembling of the device.

This application is a continuation in part of my copending application filed August 23rd, 1919, Serial No. 319,350.

While I have herein shown my invention as applied to a phonograph cabinet, it will be understood that the device is readily applicable to various types of cases or cabinets requiring counterbalancing devices, and al- 90 though the invention is hereinafter de- scribed with considerable particularity, it is not to be limited thereby, in the interpretation of the appended claims, except as may be necessitated by the state of the prior 95 art.

Referring to the drawings 1 designates the main or base portion of a phonograph cabinet having a cover or hood 2 hinged at its rear edge as at 3, the hood being 100 adapted to rest upon the top of the base portion when in closed position. The hood 2 is provided with the usual bracket 4 to which is pivoted the upper end of a link 5 which depends through a slot 6 into the base and is operatively associated with the counterbalancing device indicated generally at 7, for supporting the hood in raised position.

The counterbalancing means 7 comprises, 110 in the present embodiment, a lever 8 pivoted at 9 upon a bracket 10 carried by the base.

1. Herein said bracket is mounted upon a base plate 11 of wood or the like, suitably secured to a side wall of the base, and the bracket is offset outwardly between its upper 5 and lower ends, as at 12, so as to receive the rear end of the lever between it and the base plate 11. The free end of the lever 8 is pivotally connected at 13 to the lower end of the link 5, and mounted on the lever 10 near the free end thereof is a bracket 14 (Fig. 2) having a disk portion 15 spaced from the lever 8. Extending between said disk 15 and the lever 8 is a stud 16 having mounted thereon a coiled torsion spring 17. 15 The bracket 14 is secured to the lever 8 by means of a bolt 18, the bracket having edge flanges 19 for engaging the opposite edges of the lever 8 to prevent its rotation relative thereto. The portion 15 of the 20 bracket is in the form of a disk having a central opening therein for receiving the outer end of the stud 16, said stud being retained in position by suitable means such as a cotter-pin 20. 25 The spring 17 has its outer arm 21 held rigid with the disk 15 of the bracket, and the opposite or inner arm 22 of the spring is rigid with a rotatable element 23 journaled on the stud 16 between the lever 8 and the 30 spring. In order to permit of the adjustment of the spring to vary the torsion thereof the disk 15 of the bracket is provided with an inwardly projecting flange 24 notched to provide a series of ratchet teeth 35 25 adapted to receive the arm 21 (Figs. 2 and 3). This construction permits of an easy adjustment of the spring after the parts have been assembled. The opposite arm 22 of the spring may engage with a stud 26 40 on the rotatable element 23.

In order to effect a rotation of the element 23 as the hood 2 of the cabinet is raised or lowered, and thereby unwind or wind up the spring 17, I herein provide intermeshing teeth on the bracket 10 and rotary element 23 in the form of gear segments 27 and 28. To permit of the swinging movements of the lever 8 and at the same time guide it in such movements, the bracket 10 45 may be provided with an arcuate slot 29 in which a pair of studs 30 mounted on the lever 8 and carrying washers 30^a are arranged to operate.

As the hood is swung upwardly upon its 55 hinge 3, the lever 8 is correspondingly swung upwardly on its pivot 9. In this operation the rotatable element 23 is rotated, by reason of the engagement of its gear segment 28 with the gear segment 27 of the bracket, to 60 unwind the spring 17, upward movement of the hood being limited by the upper of the two studs 30 abutting the upper end of the arcuate slot 29. As the hood is swung downwardly, the element 23 is actuated to wind 65 up the spring 17, by engagement of the ro-

tatable gear segment 28 with the stationary gear segment 27, the tension gradually increasing as the hood moves toward the horizontal. In order that the increased tension upon the spring will not operate to resist 70 with such increasing effectiveness the descent of the hood that the latter may not be counterbalanced in the lower positions, the gear segments 27 and 28 may be formed with eccentric pitch lines so that the effective 75 radius of the element 23 is gradually increased as the hood moves downwardly, thus counteracting to the necessary degree the increasing spring tension. The parts are so proportioned that as the hood approaches 80 its closed position, the gear segment 28 of the element 23 disengages from the segment 27 of the bracket and the final tooth 28^a in the segment 28 passes out along the periphery of a cam 31 formed on the bracket 85 10 in continuation of the segment 27. The cam 31 is so constructed that the direction of force exerted by the spring-actuated member 23 upon the bracket 10 changes progressively from an approximately perpendicular relation to the longitudinal axis of the lever 8 when the gear segments 27 and 28 are in mesh, to an approximately parallel relation to that axis when the hood is in its closed position. When 90 the parallel relation referred to is attained, the parts are virtually in a dead center position as respects the tendency for movement of the lever 8 under the action of the spring. Coincident with the deflection of the line of 95 force, occurring upon the engagement of the tooth 28^a with the cam 31, friction between those members increases progressively during the final closing movement of the hood and assists in preventing a sudden 100 drop of the hood.

It will thus be seen that while the gear segments are in mesh, the lever 8 is actuated to support and counterbalance the weight of the hood. As the hood is lowered the eccentric pitch line of the segments serves to graduate the force exerted upon the bracket 110 4 proportionate to the weight supported at that point in the progressively lowered positions of the hood. As the hood approaches 115 its lowermost position the segments disengage, the tooth 28^a passes out upon the cam 31 with the effect of rapidly reducing the lifting force in the lever 8 and interposing friction to resist a sudden fall of the hood, 120 and finally permitting the hood smoothly to come to rest by gravity, in closed position, without being forced down or being suddenly dropped. The tooth 28^a is so disposed with respect to the cam 31 that while 125 the hood is closed the spring torque exerted upon the lever 8 operates in a line of force approximately parallel to the longitudinal axis of the lever and consequently no lifting force is sustained by the hood and cabinet 130

sides in that position, and no resulting constant strain tending to distort those parts.

For the purpose of facilitating the assembling of the parts, the pivotal connection between the link 5 and lever 8 is made detachable. Herein for this purpose the pivot stud 13 is provided on its inner end with an extending lug 33 and the opening in the lower end of the link 3 is provided with an angularly-extending notch 34. The lug and notch are so arranged that when the link and lever are brought into alignment the parts may be assembled but when the parts are secured in position with the link and lever out of alignment, said link and lever are held against detachment.

It will be seen that I have provided a counterbalancing device for phonographs which is of a very practical character. The parts operate smoothly without perceptible noise, and the torsional spring is capable of very effectively counterbalancing the hood. Moreover, the arrangement of the gear segments to permit the hood to descend freely as it approaches its horizontal position insures that the hood will remain closed when it is so desired, and the cabinet frame relieved from distortion by constant strain. Should the spring become worn or weakened in use, it may be very easily adjusted, and the difficulty commonly experienced in assembling disconnected parts of a device within the case is overcome by the detachable connection between the members secured to different parts of the cabinet.

I claim as my invention:

1. The combination with a stationary part and a part movable relative thereto by the action of gravity, of means for supporting the movable part in equilibrium when in open position comprising a torsion spring adapted to operably oppose the weight of said movable part, and means for automatically controlling the effective force of said spring in counterbalancing proportion to the weight sustained thereby through the range of open positions of said movable part.

2. The combination with a stationary part and a part movable in swinging relation thereto, of means for counterbalancing the movable part including a torsion spring adapted to operably oppose the weight of said movable part, and means associated with said spring operable in the proximately closed positions of said movable part to materially diminish the effective opposition of said spring.

3. The combination with a stationary part and a movable part hinged thereto, of counterbalancing means mounted on said stationary part and operatively connected with said movable part comprising a spring, a rotary element operable to deflect said spring, and means for effecting the rotation of said elements by the movements of said

movable part, said counterbalancing means being adapted to support said movable part in a condition of balance throughout its range of open positions and to discontinue said support when said movable part is in approximately closed position.

4. In a phonograph or like cabinet having a base and a hood hinged thereon, the combination therewith of means for yieldingly supporting the hood in raised position comprising a fixed member mounted in said base, an element having operable connection with said hood and having engagement with said fixed member whereby said element is rotated by swinging said hood, and a torsion spring adapted to be deflected by the rotation of said element.

5. In a cabinet having a base, a pivoted cover and means for counterbalancing the weight of said cover in open position, in combination with means to arrest the action of said counterbalancing means upon said cover in closed position, comprising a fixed element interengaging with a rotary element and coacting to deflect the operative force of the counterbalancing means in a neutral direction.

6. In a cabinet having a base and a pivoted cover, the combination of means for counterbalancing the weight of said cover in open position and being adapted to diminish in effect as said hood approaches closed position, with means for interposing frictional resistance progressively increasing as the effect of said counterbalancing means decreases.

7. In a cabinet, in combination with a base having a hinged cover, means for counter-balancing the weight of said cover in open position, said means including a torsion spring and a plurality of intermeshing gear segments having pitch lines eccentric to their centers and adapted to compensate for the increasing torsion developed in winding said spring.

8. In a phonograph or like cabinet, the combination with a base and a hinged hood, of a member pivoted to the hood and depending into the base, a lever pivoted in the base and pivotally connected to said member, and spring actuated means associated with said lever for counter-balancing said hood, said means provided with devices for restraining said counter-balancing action when said hood is in closed position.

9. In a cabinet for phonographs or the like, the combination with a base having a hinged hood, of means for yieldingly supporting said hood in raised position comprising a lever pivoted in said base and having operable linked connection with said hood, and spring controlled means including a pair of coacting toothed elements for actuating said lever to support said hood.

10. In a cabinet, the combination with a

base having a hinged cover, means for counter-balancing the action of gravity upon the cover in open position, said means including gear elements adapted to intermesh and having pitch lines eccentric to their centers whereby the variable effect of the action of gravity upon said cover within its range of open positions is opposed in the variable degree necessary to maintain said cover in equilibrium.

11. In a cabinet having a base and a hinged cover, means for counter-balancing the action of gravity upon said cover in open position in combination with means for restraining the action of said counter-balancing means upon said cover when it approaches closely to and is in closed position.

12. In a cabinet for phonographs or the like comprising a base and a hinged hood, a member pivoted to the hood and depending into said base, a bracket mounted in the base and having in association therewith a gear segment and a cam, a lever pivoted to said bracket and to said depending member, a rotary element pivoted on said lever and having teeth arranged to mesh with said gear segment, and a torsion spring arranged to be wound and unwound by the rotation of said rotary element, said rotary element being adapted to engage progressively said gear segment and said cam as the said hood is raised or lowered, said cam and said rotary element coacting to develop increasing friction therebetween with the advance of their interengagement.

13. In a phonograph or like cabinet, having a base and a hood, means for yieldingly supporting said hood in raised position comprising a member depending from said hood, a bracket mounted on said base, a fixed gear segment associated with said bracket, and a spring-actuated rotatable gear element associated with said member, said gear segment and gear element being adapted to interengage and resist the weight of said hood in raised position, and to disengage and cease such resistance when said hood is in closed position.

14. The combination with a stationary part and a part movable relative thereto by the action of gravity, of means operatively connected with said parts for yieldingly supporting the movable part comprising a fixed element having an irregular gear segment, a rotatable mutilated gear element, and a torsion spring element actuating said rotatable element, said elements coacting to counterbalance said movable part in raised position, to diminish the lifting force exerted by them as the movable part approaches its normal position, and to wholly discontinue said force when said movable part is normally at rest.

15. In a cabinet for phonographs or the

like, the combination with a base having a hinged hood, of means for yieldingly supporting the hood in raised position, comprising a member pivoted to the hood and depending into the base, a torsion spring, and means for effecting the winding and unwinding of said spring in the swinging movements of said hood, said means including a pair of intermeshing gear segments having pitch lines eccentric to their centers and adapted to compensate for the increasing torsion developed in winding said spring.

16. In a cabinet for phonographs or the like, the combination with a base having a hinged hood, of a member pivoted to the hood and depending into the base, a lever pivoted in the base and pivotally connected to said member, a bracket carried by said lever, a rotary element pivoted on the lever and having gear teeth thereon, a torsion spring having one end attached to said bracket and the other end attached to said rotary element, a second bracket mounted on the base and having a stationary gear element thereon with which the teeth of said rotary element are adapted to mesh, said rotary element and said stationary gear element cooperating to effect the opposition in counterbalanced relation of the variable tension of said torsion spring to the variable proportion of the weight of said hood supported by said pivoted member through the range of swing of said hood when raised from said base.

17. In a cabinet for phonographs or the like, comprising a base and a hinged hood, a member pivoted to the hood and depending into the base, a bracket mounted in the base and having in association therewith a gear segment and a cam, a lever pivoted to said bracket and to said depending member, a rotary element pivoted on said lever and having teeth arranged to mesh with said gear segment, and a torsion spring arranged to be wound and unwound by the rotation of said rotary element, said rotary element being adapted to engage progressively said gear segment and said cam as the said hood is raised or lowered, said cam being shaped to resist the spring tension transmitted by said rotary element in a gradually changing direction of force from an approximately perpendicular relation to the longitudinal axis of said lever to an approximately parallel relation to said axis when said hood is in closed position.

18. In a cabinet having a base and a pivoted hood, means in combination therewith for yieldingly supporting said hood in open position against the action of gravity comprising a fixed member mounted in said base having a series of teeth, a rotary element having reciprocal toothed engagement with said member and operatively connected to

1. said hood, and a spring arranged to be stressed by the rotation of said rotary element, the interengaging teeth upon said fixed member and said rotary element being shaped so that their progressive points of reciprocal engagement serve to transmit the stress in said spring for the support of said hood in variable degree effecting the counter-balancing of said hood in open position and neutralizing the spring stress when said hood is closed.
2. In a cabinet having a swinging hood, means for counterbalancing the hood including a pair of intermeshing gear elements one of which is adapted to rotate in the movements of the hood, means adapted to resist the rotation of said rotary element in the downward movement of said hood, and means operative in the lower positions of the hood approaching closure to permit increased effectiveness of gravity acting upon said hood in opposition to said resisting means.
3. In a phonograph or like cabinet, the combination with a base and a hood hinged thereon, of means for yieldingly supporting the hood in poised position comprising a member pivoted to the hood and depending into the base, an eccentric rotary element mounted in the base, a bracket mounted in the base, a torsion spring having one arm rigid with said bracket and the other arm rigid with said rotary element, and means for effecting rotation of said element whereby to wind and unwind said spring in the swinging movements of the hood.
4. In a cabinet having a swinging hood, means for counterbalancing the hood including a pair of interengaging elements one of which is adapted to rotate in the movements of the hood, and means adapted to resist the rotation of said rotary element in the downward movement of said hood, said elements operating in the lower positions of the hood approaching closure to permit increased effectiveness of gravity acting upon said hood in opposition to said resisting means.
5. In a cabinet for phonographs or the like, the combination with a base having a hinged hood, of means for yieldingly supporting the hood in raised position comprising a member pivoted to the hood and depending into the base, a torsion spring, and means including a pair of intermeshing gear segments for effecting the winding and unwinding of said spring in the swinging movements of said hood.
6. In a cabinet for phonographs or the like, comprising a base having a hinged hood, a pivoted member depending from the hood into the base, a torsion spring, and means arranged to be actuated by the movements of said member in the swinging movements of the hood to wind and unwind said spring comprising a pair of intermeshing gear segments adapted as the hood approaches its closed position to disengage and thereby diminish the lifting effect of said spring.
7. In a phonograph or like cabinet, the combination with a base having a hood, of a member pivoted to the hood and depending into the base, a lever pivoted in the base and pivotally connected to said member, a stationary gear element in the base, rotary gear element mounted on said lever and meshing with the stationary gear element, and a torsion spring having one end fixed and the other end rotatable with said rotary gear element.
8. In a cabinet for phonographs or the like, the combination with a base having a hinged hood, of a member pivoted to the hood and depending into the base, a lever pivoted in the base and pivotally connected to said member, a bracket carried by said lever, a rotary element pivoted on the lever and having gear teeth thereon, a torsion spring having one end fixed to said bracket and the other end fixed to said rotary element, a second bracket mounted on the base and having a stationary gear element thereon with which the teeth of said rotary element are adapted to mesh, said gear elements being adapted to disengage as the hood approaches its closed position, and means for preventing the rotation of said rotary element by said spring upon such disengagement.
9. In a phonograph or like cabinet, the combination with a base and a hood, of means for yieldingly supporting the hood in raised position, comprising a member depending from the hood into the base, a bracket mounted on one wall of the base and offset outwardly in its central portion from said wall, a lever pivoted on the inner side of said bracket and having a guide stud thereon, there being an arcuate slot in the bracket for receiving said stud, and spring means carried by said lever and adapted to exert a lifting effect on said hood.
10. In a phonograph or like cabinet, the combination with a base having a hinged hood, of a member pivoted to the hood and depending into the base, a lever pivoted to the base and having a detachable connection with said member, and means actuated in the swinging movements of said lever to resist in progressive increasing and decreasing degree the downward swinging movement of said hood.
11. In a cabinet for phonographs or the like, the combination with a base and a hood, of means for yieldingly supporting the hood in raised position comprising a member pivoted to the hood and depending into the base, a lever pivoted in the base and detachably connected to said member,

and means including a spring tending to effect an upward swinging movement of said lever with progressively increasing and decreasing force.

- 5 29. In a cabinet for phonographs or the like, the combination with a base having a hood, of means for yieldingly supporting the hood in raised position comprising a member depending from the hood into the 10 base, a rotary element mounted in the base, a bracket, a stud mounted in said bracket upon which said rotary element is journaled, a torsion spring surrounding said stud and having one end fixed to the bracket and 15 the other end fixed to said rotary element, and means operatively associated with said depending member to effect the rotation of said element whereby to wind and unwind said spring in the movements of the hood.
- 20 30. In a cabinet for phonographs or the like, the combination with a base having a hood, of means for yieldingly supporting the hood in raised position comprising a member depending from the hood into the 25 base, a rotary element mounted in the base, a bracket having a disk portion provided

with a series of ratchet teeth and having a stud upon which said rotary element is journaled, a torsion spring surrounding said stud and having one end engaging in one 30 of said teeth of the bracket and the other end fixed to said rotary element, and means operatively associated with said depending member to effect the rotation of said element whereby to wind and unwind said 35 spring in the movements of the hood.

31. In a phonograph or like cabinet, the combination with a base and a hinged hood, of a member pivoted to the hood and depending into the base, a lever pivoted in 40 the base and pivotally connected to said member, a spring acting upon said lever to resist the downward swinging movement of the hood, means other than spring means operable to diminish the lifting effect of 45 said spring as the hood is moved to its closed position, and means for adjusting the tension of said spring.

In testimony whereof, I have hereunto set my hand.

WILHELM GEDOR ALDEEN.
